UNITED STATES PATENT OFFICE.

OSCAR FALKENWALDE, OF BALTIMORE, MARYLAND, ASSIGNOR OF ONE-HALF TO OSCAR TESCHNER, OF BALTIMORE, MARYLAND.

WATER-GAS BURNER.

1,248,835.

Specification of Letters Patent. Patented Dec. 4, 1917.

Application filed January 3, 1917. Serial No. 140,395.

To all whom it may concern:

Be it known that I, OSCAR FALKENWALDE, a citizen of the United States, residing in the city of Baltimore and State of Maryland, have invented certain new and useful Improvements in Water-Gas Burners; and I do hereby declare the following to be a full, clear, and exact description of the invention, such as will enable others skilled in the art 10 to which it appertains to make and use the same.

The invention relates to a water gas burner.

The object of the present invention is to 15 improve the construction of hydrocarbon burners and to provide a simple, practical and efficient water gas burner of strong, durable and inexpensive construction designed for use in furnaces and various other places 20 and equipped with means for simultaneously vaporizing oil and water and causing a commingling of the same and discharging the mixture in a plurality of jets whereby the burner will develop intense heat at the 25 minimum cost.

A further object of the invention is to provide a burner of this character adapted to be easily primed and readily started and equipped with an automatic valve for controlling the inlet of the water to feed the same as required and prevent a flooding or excess of water when a gravity or other pressure feed is employed.

With these and other objects in view, the 35 invention consists in the construction and novel combination of parts hereinafter fully described, illustrated in the accompanying drawings and pointed out in the claims hereunto appended; it being understood that various changes in the form, proportion, size 40 and minor details of construction, within the scope of the claims, may be resorted to without departing from the spirit or sacrificing any of the advantages of the invention.

45 In the drawings:

Figure 1 is a side elevation of a burner constructed in accordance with this invention.

Fig. 2 is a vertical sectional view of the 50 same.

Fig. 3 is a horizontal sectional view on the line 3—3 of Fig. 1.

Fig. 4 is a reverse plan view of the superimposed spider or casing.

55 Like numerals of reference designate cor-

responding parts in the several figures of the drawings.

In the accompanying drawings in which is illustrated the preferred embodiment of the invention, the water gas burner comprises in its construction a base 1 constructed of suitable metal and preferably concavo-convex and provided with a marginal flange 2 curved upwardly and forming a peripheral groove and constituting the outer wall of the 65 base. The base is circular in plan view and its upper face may be provided with a lining 3 of more refractory material than the body of the base, which is adapted to operate as a combined starting cup and reflecting element. The upper face of the base is convex and presents an inclined surface and the oil which is adapted to drop upon the base in the starting of the device will run down the sides or inclined faces of the 70 base and collect in the marginal groove or gutter if the supply should be more or less excessive. This will prevent any of the oil from being wasted and will insure a burning of all of the oil used in starting the 75 burner.

The base is provided with a central opening 4 in which is secured a water conduit 5 illustrated in the accompanying drawings as consisting of a plurality of pipe fittings 85 and couplings and receiving an inner oil conduit 6 extending upwardly through the outer water conduit and forming an intervening water space or passage between it and the water conduit. A coupling 7 is connected with the lower end of the oil conduit and the water conduit is provided at the bottom with a T-coupling 8 forming a lateral connection for the water supply pipe 9.

The oil pipe and water pipe are designed 95 to be connected with suitable tanks or other sources of supply (not shown) and the feed may be by gravity or any other pressure. The outer water conduit is provided below the base with a lock nut 10 and it has a reducing nipple 11 located above the base and it is provided at the upper end with a valve seat 12. The base is firmly clamped between the reducing nipple 11 and the lock nut 10, a spacing sleeve 13 being interposed between 100 the lock nut and the lower face of the base, as clearly illustrated in Fig. 2 of the drawings.

The valve seat 12, which is beveled, is formed by the upper end of the reducing 110

J. FELBEL.

TYPE WRITING MACHINE.

APPLICATION FILED FEB. 24, 1917.

UNITED STATES PATENT OFFICE.

JACOB FELBEL, OF NEW YORK, N. Y., ASSIGNOR TO REMINGTON TYPEWRITER COMPANY, OF ILION, NEW YORK, A CORPORATION OF NEW YORK.

TYPE-WRITING MACHINE.

1,248,836.

Specification of Letters Patent.

Patented Dec. 4, 1917.

Application filed February 24, 1917. Serial No. 150,666.

To all whom it may concern:

Be it known that I, JACOB FELBEL, citizen of the United States, and resident of the borough of Manhattan, city of New York, in the county of New York and State of New York, have invented certain new and useful Improvements in Type-Writing Machines, of which the following is a specification.

10 My invention relates to typewriting machines, and more particularly to dust guards for protecting the pivotal bearings of the type bars.

As is well understood rubbings, comprising particles of sand, rubber and paper, fall from the front face of the platen in a front-strike typewriting machine and find their way into the type bar bearings and clog the operation of the type actions, unless efficient means are provided to prevent this. It has been found in practice that such rubbings will also find their way into the bearings from the rear of the type bar segment, as well as from the front thereof, especially 25 when the universal bar is of such a character that it extends beyond the rear face of the segment.

The main object of my invention, generally stated, is to provide simple and efficient means for preventing such rubbings from entering the type-bar bearings from the rear of the type-bar segment.

To the above and other ends which will hereinafter appear my invention consists in the features of construction, arrangements of parts, and combinations of devices, set forth in the following description and particularly pointed out in the appended claims.

In the accompanying drawings, wherein like reference characters designate corresponding parts in the various views,

Figure 1 is a detail fore and aft vertical sectional view, showing a number of parts of a front-strike typewriting machine, with my invention embodied therein.

Fig. 2 is a detail rear view of the same.

Fig. 3 is a detail fragmentary perspective view of the same, showing in addition the

connections from the universal bar to the escapement.

Fig. 4 is a detail fragmentary fore and aft vertical sectional view of a modified form of the construction.

Figs. 5 and 6 show in vertical section and rear elevation respectively a further modified form of construction.

Figs. 7 and 8 are corresponding views of a still further modification.

Figs. 9 and 10 are corresponding views of another form of construction embodying my invention.

Figs. 11 and 12 are corresponding views illustrating the 6th form of construction embodying my invention.

Fig. 13 is a detail fragmentary top plan view of the parts represented in Fig. 12.

Fig. 14 is a detail face view of the blank from which the universal bar and supporting member shown in Figs. 11 to 13, inclusive, are formed.

Referring first to Figs. 1, 2 and 3 it will be understood that a substantially vertically disposed type-bar segment, designated as a whole by the reference numeral 1, is mounted in the usual or any suitable manner below the platen 2. In the present instance the segment is a solid or closed segment with the rear face 3 thereof in a plane which is forward of the front face of the platen. The lower edge of the segment is slotted through from front to rear, the heel 4 of a type bar 5 working in each radial slot 6, so that each type bar is guided in its movement by the side walls of the slot in which it works. The type bars are mounted on a pivot wire 7, received in a groove 8 in the rear face of the segment at the slotted portions thereof. The slots 6 are closed on their upper sides by a continuous segmental flange or rib 9, which as heretofore overlies the heels of the type bars which work in the slots. Each type bar has a recess a to enable it to clear the part 9 in the movement of the type-bar to printing position. The said flange or rib 9 constitutes a forwardly extending dust guard which tends to prevent

60

the admission of falling particles of dust or grit from entering the bearings of the type-bars from the front of the segment. The type-bars may be actuated by the usual 5 or any suitable means and each bar is provided at its heel with a shoulder or cam 10 which, as the type approaches the printing position, strikes or co-acts with the forward edge of a segmental universal bar 11. It 10 will be observed that the universal bar works in a segmental groove or recess in the rear face of the segment and extends beyond the such rear face to a position where, unprotected, it would catch rubbings which drop 15 from the front face of the platen to the rear of the segment; and such rubbings eventually would be apt to work their way into the type-bar bearings, injuriously affecting them and also interfering with the 20 free and true operations of the type-bars. By my invention this is all prevented.

In each of the constructions shown I have provided a dust guard or shield which overlies the universal bar in rear of the type-bar segment and which preferably is of such curvature and length as to cover or protect 25 all of the slots at the rear side of the segment and prevent particles of grit falling from the platen to the rear of the segment 30 from lodging on the universal bar and entering the slots. This dust guard or shield is either fixed to, carried by, or formed integral with the universal bar, and hence moves therewith in the movements of the 35 latter caused by the striking of the type-bars.

In the construction shown in Figs. 1, 2 and 3 the curved dust shield is shown formed integral with the universal bar 11, and comprises a vertically disposed wall 12 connected with a downwardly and rearwardly inclined roof or cover 13, which may be designated as the dust guard proper. The forward upper edge of the roof normally bears 40 against the rear face 3 of the segment above the rear ends of the slots 6. The roof 13 at each end may be formed with an extension 45 14 which closes the space between the roof and universal bar at the ends thereof, as and best shown in Fig. 3. It will be understood from an inspection of Fig. 2 that the 50 dust guard is segmental, conforming in general contour to the universal bar. The combined universal bar and dust guard thus 55 formed is supported and guided in its movements by any suitable means such as by guide pins 15, each riveted at one end to the dust shield and working loosely at its other end in a guide opening in the segment.

60 It will be understood that in this form of construction the inclination of the roof 13 of the dust guard tends to shed the falling particles. It will also be understood that even though the dust shield be moved out

of contact with the rear face of the segment, 65 from the full line to the dotted line position in Fig. 1, during the printing movement of the type bar, this does not affect the usefulness of the dust guard since it is only when the dust guard is in its normal rest position 70 that erasures are made on the paper in the machine and at that time the universal bar and the type-bar slots are fully covered and protected by the dust guard.

The universal bar may be operatively connected to the escapement by any suitable means. In the present instance I have shown a link 16 pivoted at one end, at 17, to a dog rocker 18. The opposite end of the link is bifurcated and connected by the forward arms thereof, as at 19, to the dust shield. The dog rocker is thus under control 80 of the universal bar to control the escapement wheel 20, and paper carriage, not shown.

In the construction shown in Fig. 4 the segment 1^a is made thicker or heavier adjacent to the top walls 9 of the slots and is provided with a segmental recess 21 in the rear face thereof, said recess being concentric with the recess in which the universal bar works. The dust guard is shown made integral with the universal bar 11 and is formed with an inclined roof 13^a from which projects forwardly a segmental flange 22. 95 This flange is received in the segmental groove or recess 21 in the rear face of the segment and remains therein at all times. In other words, the length of the flange 22, fore and aft of the machine, is such that it 100 cannot be wholly withdrawn from the groove 21 in the rearward movement of the dust guard with the universal bar. By reason of this fact the universal bar and rear ends of the slots are protected at all times, irrespective of whether the machine is in operation or at rest. The combined universal bar and dust guard shown in this figure may be supported on the segment by guide pins 15^a riveted to a suitable sheet metal arm or upright 23 which in turn may be riveted as 110 at 24 to the universal bar.

The construction shown in Figs. 5 and 6 is similar to that last described except that the flange 22 is omitted, the upper edge of the roof 13^b bearing against the rear face 3 of the segment when the shield is in normal position. The other parts of these figures which correspond to those previously described are designated by corresponding reference characters, 15^b designating the supporting pins.

In the construction shown in Figs. 7 and 8 the universal bar 11 and dust shield are integral, the parts forming a single member which is substantially U-shaped in cross-section. The forward edge portion of the segmental roof 13^c of the dust shield ex-

tends into a recess, or segmental groove 25 in the rear face of the segment, as in the construction disclosed in Fig. 4, and with like effect. Supporting and guiding pins 5 15^a are riveted directly to the dust guard and work in guide openings in the segment.

In the construction shown in Figs. 9 and 10 the dust guard and universal bar are made of separate parts but are fixedly connected together. This enables the dust guard to be made from thinner and lighter stock than that from which the universal bar is formed. In this construction the dust guard has an inclined roof 13^a which bears at its 15 forward edge against the rear face of the segment. The dust guard is formed with perforated ears 26 secured by means of bolts and nuts, 27 and 28, respectively, to perforated ears 29 formed on an upstanding flange 30 on the universal bar 11. This 20 flange carries guide pins 15^a by which the universal bar and dust guard are movably supported on the segment.

The construction disclosed in Figs. 11 to 25 14, inclusive, is similar to that shown in Figs. 5 and 6, except that in the former the universal bar and dust guard are made as separate parts. Thus, in Figs. 11 to 14, the universal bar 11 is recessed at its rear edge, 30 as at 31, for the reception of lugs 32 formed on the lower edge of an inclined roof 13^a of the dust guard. At the points where the lugs 32 are received in the recesses 31 the universal bar and dust guard may be connected by riveting, spot-welding or brazing the members together. A suitable upwardly projecting supporting arm or plate 33 may be formed on the universal bar for supporting the guide pins 15^a.

40 In each of the modified forms of construction shown extensions corresponding to the extensions 14 in Figs. 1, 2 and 3 may be provided, either on the universal bar or dust guard, to span the end openings between them. These extensions are designated in Figs. 4, 6, 8 and 10 by the reference characters 14^a, 14^b, 14^c and 14^d, respectively.

It will be observed, moreover, that in each 50 of the constructions disclosed the member comprising the universal bar and dust guard is trough-shaped in cross-section, one side or portion thereof constituting a universal bar and the other side or portion constituting the overlying dust guard which protects the universal bar and the slots at the rear of the segment.

In all instances but one the dust guard is formed or provided with a downwardly sloping or inclined roof or portion, whereby 60 the descending rubbings or particles tend to fall away and behind upon striking the roof. Any particles that may remain on the roof are, however, shaken off and fall to the bottom of the machine or upon the table during

the vibration of the dust guard with the 65 universal bar under the printing action of the type-bars.

Various changes may be made without departing from my invention.

What I claim as new and desire to secure 70 by Letters Patent, is:

1. In a typewriting machine, the combination of a closed type-bar segment, a series of type-bars carried thereby, a dust guard mounted to extend rearwardly normally beyond the rear side of said segment and co-acting therewith to prevent the admission of dust to the bearings of the type-bars from the rear of the segment, said dust guard being movable at each printing operation. 80

2. In a typewriting machine, the combination of a substantially vertically disposed type-bar segment slotted at its lower edge, a series of type-bars pivoted in the slots of said segment, a universal bar actuated by said type-bars and normally extending rearwardly beyond the segment, and a dust guard carried by and arranged over and covering said universal bar in the rear of the segment. 90

3. In a typewriting machine, the combination of a substantially vertically disposed closed type-bar segment slotted at its lower edge from front to rear, type-bars which work in said slots, and a movably mounted dust guard arranged in the rear of the segment and which in its normal position extends rearwardly from the segment and above the rear open ends of the slots and prevents the admission of grit thereto from the rear of the segment. 95

4. In a typewriting machine, the combination of a substantially vertically disposed type-bar segment slotted at its lower edge from front to rear, type-bars which work in said slots, a universal bar actuated by the type-bars, and a dust guard carried by the universal bar and which in its normal position extends rearwardly from the segment and above the rear open ends of the slots and prevents the admission of dust or grit thereto from the rear of the segment. 100

5. In a typewriting machine, the combination of a substantially vertically disposed type-bar segment slotted at its lower edge from front to rear and provided with a fixed forwardly extending dust shield which extends to the front ends of said slots and prevents falling particles of grit at the front of the segment from entering the slots, type-bars which work in said slots, a universal bar actuated by said type-bars, and a dust guard carried by said universal bar and which in its normal position extends rearwardly from the segment and above the rear open ends of said slots and prevents the admission of grit thereto from the rear of the segment. 115

60

In all instances but one the dust guard is formed or provided with a downwardly sloping or inclined roof or portion, whereby the descending rubbings or particles tend to fall away and behind upon striking the roof. Any particles that may remain on the roof are, however, shaken off and fall to the bottom of the machine or upon the table during

6. In a typewriting machine, the combination of a series of upwardly and rearwardly striking type-bars, a segment on which said type-bars are mounted, a universal bar actuated by said type-bars and extending beyond the rear side of the segment and arranged beneath the printing point, and a dust guard carried by the universal bar and arranged between the latter and the printing point and normally extending beyond the rear side of the segment to prevent particles of grit falling to the rear of the segment from lodging on the universal bar and working their way into the bearings of the type-bars.
7. In a typewriting machine, the combination of a substantially vertically disposed type bar segment slotted through the lower edge thereof to the rear side of the segment, a series of upwardly and rearwardly striking type-bars which work in said slots, a segmental universal bar actuated by said type-bars and arranged beneath the printing point, and a segmental dust guard carried by said universal bar and arranged between the latter and the printing point and above the rear ends of said slots to prevent falling particles of grit from lodging on the universal bar and from entering the slots from the rear of the segment.
8. In a typewriting machine, the combination of a substantially vertically disposed type-bar segment slotted from front to rear to form bearing slots, a series of upwardly and rearwardly striking type-bars pivoted to work in said slots, a universal bar actuated by said type-bars, and a curved dust guard arranged in the rear of the segment and fixed to said universal bar and extending above the same and above the rear open ends of the slots, thus protecting the universal bar and the slots above the latter against the admission of dust or grit thereto from the rear of the segment.
9. In a typewriting machine, the combination of a substantially vertically disposed slotted type bar segment, type bars which work in the slots therein, a universal bar actuated by said type bars and when at rest projecting rearwardly behind said segment, and a movable dust guard comprising a portion that extends outwardly and downwardly behind said segment and is connected to the rear edge portion of the universal bar.
10. In a typewriting machine, the combination of a substantially vertically disposed type-bar segment, a series of upwardly and rearwardly striking type-bars carried thereby, a universal bar actuated by said type-bars, and a movable dust guard arranged over the universal bar and extending at its forward edge into the body of the segment from the rear thereof.
11. In a typewriting machine, the combination of a substantially vertically disposed slotted type-bar segment having a groove or recess in the rear face thereof, a series of type-bars mounted to work in the slots in said segment and to move upwardly and rearwardly and strike against the front face of the platen, a universal bar actuated by said type-bars, and a movable dust guard arranged over the universal bar and received at its forward edge in said groove or recess.
12. In a typewriting machine, the combination of a substantially vertically disposed slotted type-bar segment having a groove or recess in the rear face thereof, a series of type-bars mounted to work in the slots in said segment and to move upwardly and rearwardly and strike against the front face of the platen, a universal bar actuated by said type-bars, and an inclined dust guard arranged over and to move with the universal bar and provided with a forwardly extending portion which occupies said groove or recess.
13. In a typewriting machine, the combination of a segmentally arranged series of upwardly and rearwardly striking type-bars, a segment on which said type-bars are mounted, and a substantially trough-shaped curved member arranged on the rear side of the type-bar segment, one portion of which member constitutes a universal bar with which the type-bars co-act and another portion of which constitutes an overlying dust guard that co-acts at its forward edge with the segment to prevent particles falling in the rear of the segment from passing between the guard and segment and from lodging on the universal bar.
14. In a typewriting machine, the combination of a substantially vertically disposed slotted type-bar segment provided with a segmental groove in the rear face thereof, a series of upwardly and rearwardly swinging type-bars mounted to work in said slots, and a substantially trough-shaped curved member one portion of which constitutes a universal bar with which the type-bars co-act and the other portion of which extends above the upper ends of said slots and into said groove and constitutes a dust guard.
15. In a typewriting machine, the combination of a slotted type bar segment, a series of type bars, a universal bar actuated thereby and projecting normally beyond the rear side of said segment, and a member extending upwardly from the universal bar and also forwardly to the rear side of the segment; said member thereby serving to prevent falling particles from lodging on the universal bar and being carried thereby into slots of the segment.

16. In a typewriting machine, the combination of a substantially vertically arranged slotted type bar segment formed on its rear face with two concentric recesses 5 one above the other, a series of upwardly and rearwardly striking type bars, a universal bar arranged to work in the lower one of said recesses, and a dust-guard arranged over the universal bar and received 10 at its forward edge in the upper one of said recesses.

17. In a typewriting machine, the combination of a type-bar segment having a segmental groove on its rear side, a series of 15 type-bars, and a combined universal bar and dust guard, the latter extending over the universal bar and protecting it from falling particles of grit and having a forwardly

extending segmental portion that occupies and reciprocates in said groove.

18. In a typewriting machine, the combination of a type-bar segment having a segmental groove on its rear side, a series of type-bars, and a combined universal bar and dust guard, the latter having a downwardly sloping roof-portion and a forwardly extending segmental portion that occupies and reciprocates in said groove.

Signed at the borough of Manhattan, city of New York, in the county of New York 20 and State of New York this 21st day of February, A. D. 1917.

JACOB FELBEL.
